STRIPPER FEET FOR BUTTONHOLE ATTACHMENTS

John P. Enos, Union, N. J., assignor to The Singer Manufacturing Company, Elizabeth, N. J., a corporation of New Jersey

Application September 22, 1948, Serial No. 50,482

7 Claims. (Cl. 112—77)

1

This invention relates to buttonhole attachments for domestic sewing machines and particularly to that type of attachment which is removably secured to and carried wholly by the presser-bar of the machine and actuated by the reciprocating needle-bar, as distinguished from that type which is secured to the cloth-plate or other portions of the machine frame.

Attachments of this nature, as heretofore constructed, have included a work-engaging and work-shifting element having a rectangular opening beneath which the buttonhole is formed in the underlying workpiece. This opening must be sufficiently large to accommodate the largest buttonhole to be made and therefore, necessarily, is of substantial dimensions. While attachments of this nature have been satisfactory for producing buttonholes in most materials, it has been found that in very thin and sleazy materials there is a tendency for the material to "flag," that is to pulsate with the up and down movements of the needle. This flagging of the material has caused the skipping of stitches and has interfered with the proper stitching of the buttonhole.

This invention has as an object to provide, in a presser-bar-carried type of buttonhole attachment, a presser device or stripper-foot which will bear upon the work adjacent the needle during that portion of the stitch forming cycle when the needle is entering and withdrawing from the material and which will thereafter be lifted from the material to permit the material to be shifted relative to the needle to cause the next stitch to be positioned properly.

Another object of the invention is to provide, in a buttonhole attachment of the type above described, an intermittently actuated stripper-foot mounted on a frame carried by the presser-bar and for raising and lowering the foot from a lever also carried by said frame and actuated by the reciprocating needle-bar of the machine.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby, will be readily understood by those skilled in the art.

In the drawings,

Fig. 1 is a front elevation of a portion of a sewing machine showing the improved button-hole attachment applied thereto.

Fig. 2 is an elevation looking from the left of

2

Fig. 1, with the rear portion of the attachment broken away.

Fig. 3 is a vertical sectional view taken substantially on the line 3—3 of Fig. 1, also with the rear portion of the attachment broken away.

Fig. 4 is a plan view of the forward end portion of the attachment with the presser-bar and needle shown in section.

Fig. 5 is an exploded perspective view of the frame for securing the attachment to the presser-bar of a sewing machine, of the presser device which is slidingly mounted on said frame, and of the means actuated from the needle-bar for lifting the presser device.

10 Referring more specifically to the drawings, the invention is disclosed as embodied in a buttonhole attachment adapted to be secured to the presser-bar 1 and to be actuated by the reciprocatory movements of the needle-bar 2 of a conventional domestic sewing machine. In the drawings the bracket-arm head of the sewing machine is designated as 3 and the work-supporting cloth-plate as 4. The cloth-plate carries the usual throat-plate 4a.

15 The stitch-forming mechanism of the machine is shown as comprising an eye-pointed thread-carrying needle 5 carried by the needle-bar and a cooperating loop-taker 6 journaled beneath the cloth-plate 4. The needle 5 is secured to the needle-bar 2 by a clamp-collar 7

20 secured to and reciprocating with the needle-bar and having a cylindrical portion 7a which actuates the buttonhole attachment, as hereinafter described. The feeding mechanism of the sewing machine, which is rendered ineffective to

25 feed the work during the use of the buttonhole attachment, is designated generally as f.

20 The buttonhole attachment comprises a supporting frame including a bracket 8 adapted to be attached to the presser-bar 1 by a knurled thumb-screw 9, in place of the usual presser-foot, and a U-shaped sheet metal portion 10 attached to the bracket 8 as by pins 11 which project through apertures 8a in the bracket 8 and through apertures 10a in the upstanding side walls 10b, 10c of the sheet metal portion 10.

30 Rigidly secured to the under side of the portion 10 is a base-plate 12 which carries, at its under side, a slidably and pivotally mounted plate 13 having, at its front end, spaced and downturned fingers 13a. Pivotally mounted on the fingers 13a is a rectangular work-clamping member 14

35 having a serrated under surface 14a adapted to grip and shift a workpiece placed upon the cloth-plate 4. The work-clamping member 14 is

40 45 rigidly secured to the under side of the portion 10 by pins 15 which project through apertures 10b, 10c and through apertures 15a in the side walls 10b, 10c.

45 The base-plate 12 is secured to the under side of the portion 10 by pins 16 which project through apertures 10b, 10c and through apertures 16a in the side walls 10b, 10c.

50 The base-plate 12 is secured to the under side of the portion 10 by pins 17 which project through apertures 10b, 10c and through apertures 17a in the side walls 10b, 10c.

55 The base-plate 12 is secured to the under side of the portion 10 by pins 18 which project through apertures 10b, 10c and through apertures 18a in the side walls 10b, 10c.

55 The base-plate 12 is secured to the under side of the portion 10 by pins 19 which project through apertures 10b, 10c and through apertures 19a in the side walls 10b, 10c.

55 The base-plate 12 is secured to the under side of the portion 10 by pins 20 which project through apertures 10b, 10c and through apertures 20a in the side walls 10b, 10c.

55 The base-plate 12 is secured to the under side of the portion 10 by pins 21 which project through apertures 10b, 10c and through apertures 21a in the side walls 10b, 10c.

which the buttonhole is sewed in the underlying workpiece.

Pivotaly mounted on a stub shaft 15, journalled in apertures 16 in the upstanding side walls 10^b, 10^c of the bracket portion 10, is an operating lever 17 having a forked end 17^a which straddles the cylindrical portion 7^a of the needle-clamp collar. Fixed to the shaft 15 between the side walls 10^b, 10^c, by a set screw 18, is a barrel cam 19. Also secured to the shaft 15 at the outer face of the side wall 10^c is a ratchet wheel 20 which is engaged by a spring-pressed pawl 21 carried by the lever 17. Thus reciprocation of the needle-bar causes the operating lever to be oscillated about the stub shaft 15 and the oscillatory movements of this lever effects step-by-step rotation of the ratchet wheel 20, shaft 15 and the cam 19. Rotation of the cam 19 effects, through mechanism not disclosed, lateral vibratory movements and back and forth endwise feeding movements of the plate 13 and the work-clamping member 14 carried thereby, in timed relation with the reciprocations of the needle, to cause the stitch-forming mechanism to sew a buttonhole in that portion of a workpiece located beneath the rectangular opening 14^b in the work-clamping member 14.

All of the mechanism above described is conventional and forms no part of the present invention.

As hereinbefore indicated, it has been found that, during the sewing of a buttonhole in certain types of material, the portion of the workpiece below the opening 14^b in the work-holding member 14 tends to "flag," that is to move up and down with the needle, thereby causing the skipping of stitches and interfering with the proper formation of the buttonhole. To overcome this difficulty, this invention has provided an improved form of presser device or so-called "stripper-foot" which bears on the workpiece closely adjacent the needle and holds the workpiece down on the throat-plate 4^a at all times except during the actual shifting of the workpiece. This presser device is actuated from the oscillatory operating lever 17 and comprises an upright shank member 22 slidingly mounted in guideways 23, 24 provided by the side wall 10^b of the supporting frame 10. At its lower end the member 22 is formed with an offset portion 22^a which carries a horizontally disposed stripper-foot 25, which, as shown most clearly in Fig. 4, is adapted to bear upon the workpiece immediately behind the needle 5. At its upper end the presser member 22 is formed with an offset arm 22^b to which is secured one end of a coil spring 26, the other end of the spring being connected with the side wall 10^b. The spring is constantly maintained under tension and therefore constantly tends to urge the member 22 and its foot 25 downwardly to cause the foot to bear upon the workpiece. The presser member 22 is adapted to be lifted periodically, in opposition to the spring 26, by the oscillatory movement of the operating lever 17. This is effected by means of a first two-armed lifting lever 27 fulcrumed on a screw 28 threaded into an aperture 29 in the side wall 10^b (Fig. 5) with its axis parallel to the axis of the stub shaft 15. One arm 27^a of the lever 27 engages beneath the arm 22^b of the member 22 while the other arm 27^b thereof is engaged by one arm of a second two-armed lifting lever 30. The lever 30 is fulcrumed on a shoulder screw 31 which passes through an aperture 32 formed in an offset portion 10^d (Fig. 5) of the frame side

wall 10^b, and is held therein by a nut 33. The fulcrum axis of the lever 30 is transverse to the fulcrum axes of the lever 27 and the operating lever 17. The other arm 30^b of the lever 30 is bent laterally and has a downturned end portion 30^c which bears upon the upper edge of the operating lever 17 under the influence of the spring 26, acting through the arm 22^b and lever 27. During the downward movement of the lever 17 the arm 30^b of the lever 30 follows the lever 17 until the lever 30 engages an offset abutment 10^e carried by the portion 10^d of the frame member 10. Thereafter the lever 17 has a further downward movement which produces a slight lost motion between the levers 17 and 30.

During the operation of the machine, the presser member 22 is lowered with the needle until the stripper-foot 25 bears upon the workpiece. Immediately thereafter the point of needle enters the workpiece. Due to the lost motion between the levers 17 and 30 the stripper-foot continues to bear upon the workpiece while the needle continues to descend and until the point of the needle has again been raised above the workpiece. Thus the workpiece is held down on the throat-plate adjacent the needle during the critical stage of the stitch forming cycle and therefore "flagging" of the material and the difficulties heretofore caused thereby are completely obviated.

Having thus set forth the nature of the invention, what I claim herein is:

1. A buttonhole attachment for a sewing machine having a presser-bar and a reciprocating needle-bar carrying an eye-pointed needle; comprising a frame including a supporting bracket secured upon the presser-bar; a base-plate carried by said frame; a shiftable work-clamping element supported on said base-plate and provided with an opening through which a buttonhole is sewed in an underlying workpiece; means including an operating lever pivotally mounted on said frame and actuated by said needle-bar for shifting said work-clamping element; a stripper-foot engaging the workpiece adjacent the needle; and means actuated from said operating lever and including a second lever pivotally mounted on said frame and having its pivotal axis spaced from the pivotal axis of said operating lever for raising and lowering said stripper-foot in timed relation with the reciprocations of said needle-bar.

2. A buttonhole attachment for a sewing machine having a presser-bar and a reciprocating needle-bar carrying an eye-pointed needle; comprising a supporting frame secured upon the presser-bar and having a U-shaped sheet metal portion; a base-plate carried by said frame; a shiftable work-clamping element supported on said base-plate and provided with an opening through which a buttonhole is sewed in an underlying workpiece; means including an operating lever pivotally mounted on the U-shaped portion of said frame and actuated by said needle-bar for shifting said work-clamping element; a stripper-foot having a shank portion movably mounted on the U-shaped portion of said frame and a foot portion engaging the workpiece adjacent the needle; and means including a second lever pivotally mounted on the U-shaped portion of said frame and actuated by the movement of said operating lever for raising and lowering said stripper-foot in timed relation with the reciprocations of said needle-bar.

3. A buttonhole attachment for a sewing machine having a presser-bar and a reciprocating

needle-bar carrying an eye-pointed needle; comprising a supporting frame secured upon the presser-bar and having a U-shaped sheet metal portion; a base-plate carried by said frame; a shiftable work-clamping element supported on said base-plate and provided with an opening through which a buttonhole is sewed in an underlying workpiece; means including an operating lever pivotally mounted on the U-shaped portion of said frame and actuated by said needle-bar for shifting said work-clamping element; a stripper-foot having a shank portion movably mounted on the U-shaped portion of said frame and a foot portion engaging the workpiece adjacent the needle; and means actuated by said operating lever and including a lever pivotally mounted on the U-shaped portion of said frame and having its pivotal axis spaced from and parallel to that of said operating lever for raising and lowering said stripper-foot in timed relation with the reciprocations of said needle-bar.

4. A buttonhole attachment for a sewing machine having a presser-bar and a reciprocating needle-bar carrying an eye-pointed needle; comprising a supporting frame secured upon the presser-bar and affording a vertically disposed guideway; a base-plate carried by said frame; a shiftable work-clamping element supported on said base-plate and provided with an opening through which a buttonhole is sewed in an underlying workpiece; means including an operating lever pivotally mounted on said frame and actuated by said needle-bar for shifting said work-clamping element; a stripper member having a shank portion slidably mounted on said guideway and a foot portion engaging the workpiece adjacent the needle; and means including a lever pivotally mounted on said frame and having one portion connected with the shank of said stripper member and another portion operatively connected with said operating lever for raising and lowering said stripper member in timed relation with the reciprocations of said needle-bar.

5. A buttonhole attachment for a sewing machine having a presser-bar and a reciprocating needle-bar carrying an eye-pointed needle; comprising a supporting frame secured upon the presser-bar and affording a vertically disposed guideway; a base-plate carried by said frame; a shiftable work-clamping element supported on said base-plate and provided with an opening through which a buttonhole is sewed in an underlying workpiece; means including an operating lever pivotally mounted on said frame and actuated by said needle-bar for shifting said work-clamping element; a stripper member having a shank portion slidably mounted on said guideway and a foot portion engaging the workpiece adjacent the needle; and means including a pair of interconnected levers pivotally mounted on said frame, one of said levers being operatively connected with said operating lever and the other operatively connected with said stripper member, for raising and lowering said stripper-foot in

timed relation with the reciprocations of said needle-bar.

5. A buttonhole attachment for a sewing machine having a presser-bar and a reciprocating needle-bar carrying an eye-pointed needle; comprising a supporting frame secured upon the presser-bar and affording a vertically disposed guideway; a base-plate carried by said frame; a shiftable work-clamping element supported on said base-plate and provided with an opening through which a buttonhole is sewed in an underlying workpiece; means including an operating lever pivotally mounted on said frame and actuated by said needle-bar for shifting said work-clamping element; a spring depressed presser member including a shank portion slidably mounted on said guideway and a foot portion engaging the workpiece adjacent the needle; and means including a first lifting lever pivotally mounted on said frame with its pivotal axis parallel to the pivotal axis of said operating lever, one arm of said lifting lever engaging the shank portion of said presser member, and a second lifting lever pivotally mounted on said frame with its pivotal axis transverse to the axis of said first lifting lever, one end of said second lifting lever engaging said operating lever and the other end thereof engaging the other arm of said first lifting lever, said operating lever and lifting levers serving to transmit lifting movements to said presser member in timed relation with the upward movements of said needle-bar.

20 6. A buttonhole attachment for a sewing machine having a presser-bar and a reciprocating needle-bar carrying an eye-pointed needle; comprising a frame including a supporting bracket constructed and arranged to be secured upon the presser-bar; a horizontally disposed plate carried by said frame; work-clamping means supported by said plate comprising spaced work-engaging portions; means including an operating lever pivotally mounted on said frame and actuated by said needle-bar for shifting said work-clamping means; a foot constructed and arranged to engage a workpiece between said work-engaging portions of said work clamping means and adjacent the needle; and means actuated from said operating lever and including a second lever pivotally mounted on said frame and having its pivotal axis spaced from the pivotal axis of said operating lever for raising and lowering said foot in timed relation with the reciprocations of said needle-bar.
